UNITED STATES PATENT OFFICE.

GEORGE HOYT ALLEN, OF CLINTON, NEW YORK.

DESIGN FOR A PEN-RACK AND INKSTAND.

SPECIFICATION forming part of Design No. 25,839, dated July 28, 1896.

Application filed June 8, 1896. Serial No. 594,793. Term of patent 14 years.

To all whom it may concern:

Be it known that I, GEORGE HOYT ALLEN, a citizen of the United States, residing at Clinton, in the county of Oneida and State of New York, have invented and produced a new and original Design for Pen-Racks and Stands; and I do hereby declare the following to be a full, clear, and exact description of the invention, such as will enable others skilled in the art to which it appertains to make and use the same.

In the drawings, Figure 1 is a perspective view of a pen-rack and inkstand, showing my design; and Fig. 2 is a vertical transverse section view.

The leading feature of my design is a block-like stand, the front side of which is inclined in a general direction from bottom to the top, provided with a series of grooves and with continuous shoulders or ledges between said grooves, the edges of the block-like stand at the top and bottom and the edges of the shoulders or ledges being rounded.

Referring by letter to the drawings, A indicates my block-like stand and rack, having the substantially flat bottom face *a*, a substantially vertical rear wall *b*, and a flat top face *c*. This flat top face *c* is not equal in length to the bottom *a*, because the front of

the block-like stand is inclined in a general 30 direction from the bottom face *a* to the top face *c*. In this inclined front side of the stand is a series of grooves lying one above and in rear of the other in step-like order. I have shown a series of three grooves *d d' d''* and a 35 series of two continuous ledges or shoulders *e e'* between the three grooves, but the number is not material. The edges of the block-like stand are rounded at top and bottom at *f g*, and the edges of the shoulders or ledges 40 are also rounded, as at *h h'*, all of these bevels lying in substantially the plane of the inclined front side of the stand.

In the block-like stand I provide receptacles *i*, which open through the flat top face *c* 45 of the stand.

I provide a receptacle at each end for ink and one in the center for pincushion or pen-cleaner.

What I claim as new is—

The design herein shown and described for a pen-rack and stand.

In testimony whereof I affix my signature in presence of two witnesses.

GEORGE HOYT ALLEN.
